[57] CLAIM

The ornamental design for a picture framing cutter, as
shown and described.

DESCRIPTION

FIG. 1 is a perspective view of a picture framing cutter
showing my new design;

FIG. 2 is a side elevational view thereof; the opposite
side being substantially the same except for the omission
of the knobs;

FIG. 3 is a rear elevational view thereof.

FIG. 1

FIG. 2

FIG. 3
